UNITED STATES PATENT OFFICE.

CHARLES H. ELLIOTT, OF PHILADELPHIA, PENNSYLVANIA, ASSIGNOR TO H. W. BUTTERWORTH & SONS COMPANY, A CORPORATION OF PENNSYLVANIA.

CLOTH-FEEDING DEVICE FOR TEXTILE MACHINERY.

1,170,228.

Specification of Letters Patent.

Patented Feb. 1, 1916.

Application filed September 21, 1915. Serial No. 51,748.

To all whom it may concern:

Be it known that I, CHARLES H. ELLIOTT, a citizen of the United States, and resident of Philadelphia, county of Philadelphia, 5 and State of Pennsylvania, have invented an Improvement in Cloth-Feeding Devices for Textile Machinery, of which the following is a specification.

The object of my invention is to provide 10 a satisfactory cloth guiding and feeding device for feeding the cloth into and out of a conditioning or other chamber in which the cloth is subjected to treatment by heating, steaming, or otherwise, and from which 15 chamber the outside atmosphere must be excluded as far as possible while permitting the ready entrance and withdrawal of the fabric.

While my invention is especially intended 20 for what are technically known as "conditioning machines" in which the fabric is subjected to the action of steam heat at definite maintained pressure, nevertheless, I do not restrict myself to such use as the 25 apparatus is suitable for any machine in which material in sheet form is to be guided into and out of a closed chamber, while excluding, as far as possible, circulation of atmospheric air. In machines of this class, 30 the fabric is guided back and forth over numerous rollers within the chamber, and it is a tedious and time consuming operation to "thread" up such machines with fabric; and to avoid this labor, a machine once 35 "threaded" is maintained in such condition by stitching or otherwise attaching to the end of one web the beginning of the next web to be treated. The places of this union produce two-ply or three-ply thicknesses. 40 (according to the form of the union) which must be guided momentarily through the feeding opening, while at all other times the fabric is but single-ply and hence the size of the feeding opening must not only have 45 capacity for adjustment but the adjustment must take place automatically. Furthermore, with fabrics of different thicknesses, the size of the opening should vary and hence after passing a thin fabric through the machine it should automatically adjust and 50 adapt itself to the thicker fabric which may follow.

My improved apparatus provides for the above specified requirements and hence is 55 automatic in its adjustments; and is, more-

over, so constructed that the guiding portions or "rolls" are steam heated, as well as the feed box, that the fabric may be heated as it enters and any small air leakage into the machine with the fabric likewise 60 heated to a degree that its objectionable effects would not extend beyond the feed box itself.

With the above stated objects and other advantages of less nature referred to hereinafter, as the foundation for my improvements, my invention consists of certain constructions for guiding and feeding webs of material into and out of suitable closed chambers, all of which are fully described 70 hereinafter and more specifically defined in the claims.

Referring to the drawings, Figure 1 is a side elevation of one end of a textile conditioning machine showing my improvements applied thereto (but having a portion of the exhaust or return piping removed); Fig. 2 is an end elevation of the same with all of the piping in position; Fig. 3 is a side elevation of my improved guiding and feeding apparatus upon a larger scale; Fig. 4 is a sectional view through the feed box and guides, on the same scale as in Fig. 3; and Fig. 5 is a side elevation showing a modified form of my invention. 85

2 is the chamber of the machine and may be of any size or shape, and is usually formed as a long rectangular metal compartment having a large number of guide rollers over which the fabric is guided up 90 and down during its passage through the chamber to prolong the treatment, all of which is well known and common practice. The chamber is also heated by steam heat either by heating coils, free live steam, or 95 both, as the requirements may dictate, and I do not restrict myself as to any of these features. Sometimes, the fabric is led into the chamber at one end and passes out of it at the other end, thus requiring two apertures; 100 and in other cases, the fabric enters and leaves the chamber at the same end, in which operation the same guiding and feeding means may be employed for the web both on entering and leaving, and my invention 105 includes apparatus of this capacity.

3 is the feed box and comprises a passage 4 for the fabric having steam chambered walls 5, into which steam is supplied from a steam main 16 and from which the water 110

of condensation and waste may pass to the exhaust or return main 17, the water draining off by the drain pipe 17^a. The passage 4 opens at its inner end into the chamber 2 and at its outer end into the atmosphere, but has the outer end opening considerably contracted by parallel guides 6, 6. These guides are preferably formed of brass tubes with smooth outer surfaces and closely fitting through the side walls of the feed box and the top and bottom of the throat or opening to the passage (Fig. 4). In this way the opening into the chamber is much narrower than the passage 4, and is substantially sealed by the tubular guide 7, which is also preferably made of brass tubing with a polished outer surface. The diameter of the guide 7 is preferably larger than the guides 6, 6, but I do not restrict myself in this respect. All of these guides 6 and 7 are steam heated, the steam circulating through their tubular interiors. The tubular guide 7 is sometimes termed a "guide roll," but while it may be adapted to rotate in its supports, this is not necessary owing to the smoothness of its outer surface over which the cloth travels. The tubular guide 7 is cylindrical and of roller form, also for capacity to adjust different portions of its circumference into guiding position, so that in this capacity it acts as a journaled roller held in different circumferential positions to compensate for wear. In view of the fact that steam is required to circulate through guide 7, it is preferable that it be normally held against free rotation. The ends of the guide 7 are made flat and snugly fit between the end walls of the opening 4 of the feed box, and when said guide rests against the guides 6, 6, the entrance is practically air-tight, at least sufficiently so to prevent objectionable air circulation.

The guide 7 is carried on the lower ends of two swinging arms 8 secured at the top to a hinge rod 9, said rod journaled in the ends of brackets 12 extending from the end of the chamber 2. These brackets 12 are preferably made adjustable, comprising fixed parts 13 and adjustable end parts 14 extensible thereon and clamped in adjusted position by clamping bolts 15. In this way the guide 7 may be accurately alined with the guides 6, 6. The arms 8 are provided with horizontally extending arms 10 upon which are adjustably secured counter-weights 11, by which the desired pressure of the guide 7 toward the guides 6, 6, may be assured. This capacity for yieldingly holding the guide 7 toward the guides 6, 6, is important, as it counteracts the tendency of the traveling cloth to abnormally force the guide 7 away from the guides 6, 6, not only during normal feeding, but also when a seam between two webs is passing, either into or out of the chamber. In place of the

counter-weights 11, any other equivalent manner of applying yielding pressure to the arms 8 and guide 7 may be employed.

Steam is supplied to the fixed guides 6, 6, by pipes 21 leading from the steam supply pipe or main 16, and the water of condensation from said guides may pass by pipes 22 into the return main 17 (Fig. 2). The guides 6, 6, are preferably adjustable circumferentially so that when worn, new portions may be brought into guiding position, and thus maintain the accuracy of construction as well as to prevent leakage of steam and damage to the fabric.

Steam is supplied to the guide 7 in any suitable manner, but as shown, I prefer to deliver steam from the supply pipe 16 by a branch pipe 19 and a swinging pipe connection 18 opening at its lower end into the guide 7 and at its upper end having a swiveling connection with the pipe 19, said connection being axially in line with the hinge rod 9, so that not only do the arms 8 swing about the axis of rod 9, but the pipe 18 likewise swings about an axis co-incident with the axis of said rod. In this way the free movement of the tubular guide 7 is not impaired by the steam pipe connections 18, 19. Any other suitable flexible steam connection for supplying steam to the guide 7 may be employed in lieu of that shown. To enable the water of condensation and liberated air to escape from the guide 7, its opposite end is connected with a flexible tube or hose 20 leading down and discharging into the return main 17, said connection allowing of the water to drain off by gravity, whereby exhaust or low pressure steam may be employed in the apparatus. This flexible pipe 20, also enables the guide 7 to move freely while maintaining the steam supply and proper drainage. It will be manifest that, if desired, a steam supply flexible connection similar to pipe 20 may be also used on the supply end of guide 7 in lieu of the pipes 18 and 19.

As shown in Figs. 1 and 4, the fabric web passes upward from under a guide roller 23 and over the lower guide 6, thence into the chamber 2 and after treatment, passes out through passage 4 under upper guide 6 to the cloth folder or other apparatus. It will also be seen that the guide 7 rests against the opposing surfaces of the in-going and outgoing portions of the web, and hence effectually seals the space between the guides and webs against the entrance of air, but at all times is self-adjusting to suit the passage of the seam between two webs (before referred to), both into and out of the chamber. It will further be seen that this construction provides over the entrance into the passage 4 of the feed box, steam heated barriers against entrance of outside air, said barriers found in the guides 6, 6, and 7. In

cases where the width of the web entering the chamber is not of the full width of the passage 4 of the feed box and of the guides 6, 6, and 7, this may be compensated for by 5 temporarily pasting small sections of the fabric about the end portions of the guide 7 thereby thickening its end portions to close the slits which otherwise may be formed, this being merely a shop expedient to meet a 10 possible condition. In some cases the small leakage thus made possible may be no objection and the sealing of it may be omitted.

In the construction above described, it will be noted that the fabric passes in and out of 15 the same opening and in contact with the same guide 7, but it is to be understood that this is not essential as the apparatus shown may be used for guiding the fabric in one direction only, there being a separate means 20 for the entering and the leaving web portions.

In the modification shown in Fig. 5, the same guides 6, 6, and 7 are employed, but in this case the guide 7 is hung by arms 8^a to 25 swing about the axis 9^a of the upper guide 6 and make a yielding contact with the lower guide 6 or the fabric passing over it. In this case, the arms 8^a have lateral arms 10^a carrying counterweights 11^a to hold the guide 7 30 yieldingly pressed toward the lower guide 6 and upon the fabric passing thereover. It will be seen that as the guides 6 are cylindrical where they contact with the guide 7, the latter may have considerable adjustment 35 without opening any passage between it and the upper guide 6. This construction is essentially for feeding and guiding the fabric in one way only.

It will now be apparent that I have devised a novel and useful construction which 40 embodies the features of advantage enumerated as desirable, and while I have in the present instance shown and described the preferred embodiment thereof which has 45 been found in practice to give satisfactory and reliable results, it is to be understood that I do not restrict myself to the details, as the same are susceptible of modification in various particulars without departing from 50 the spirit or scope of the invention.

Having now described my invention, what I claim as new and desire to secure by Letters Patent, is:—

1. In apparatus of the character stated, a 55 chamber through which a web is passed having an entrance passage for the web, combined with feeding and guiding means for said passage comprising a fixed tubular guide over which the web is guided, a movable tubular guide movable to and from the 60 fixed guide, means for normally pressing the movable guide toward the fixed guide and upon the web passing thereover with a yielding pressure, and means for supplying a heating fluid to the tubular guides.

2. In apparatus of the character stated, a chamber through which a web is passed having an entrance passage for the web, combined with feeding and guiding means for said passage comprising a fixed tubular 70 guide over which the web is guided, a movable tubular guide movable to and from the fixed guide, means for normally pressing the movable guide toward the fixed guide and upon the web passing thereover with a yielding pressure, said guides adjustable circumferentially to enable different portions of their surfaces to be brought into opposed positions to compensate for wear, and means for supplying a heating fluid to the tubular 75 guides.

3. In apparatus of the character stated, a chamber through which a web is passed having an entrance passage for the web, combined with feeding and guiding means for 85 said passage comprising a fixed tubular guide over which the web is guided, a movable tubular guide movable to and from the fixed guide, means for normally pressing the movable guide toward the fixed guide and 90 upon the web passing thereover with a yielding pressure consisting of swinging pivoted arms carrying the tubular guide at their free ends and having counterweighted means for swinging them toward the fixed 95 guide, and adjustable means for supplying a heating fluid to the tubular guides for all positions of their relative adjustment.

4. In apparatus of the character stated, a chamber through which a web is passed having an entrance passage for the web, combined with feeding and guiding means for 100 said passage comprising a fixed tubular guide over which the web is guided, a movable tubular guide movable to and from the fixed guide, means for normally pressing the movable guide toward the fixed guide and upon the web passing thereover with a yielding pressure consisting of swinging pivoted 105 arms carrying the tubular guide at their free ends and having counterweighted means for swinging them toward the fixed guide and adjustable brackets to which the swinging arms are pivoted and by which the movable 110 guide may be adjusted parallel to the fixed guide, and adjustable means for supplying a heating fluid to the tubular guides for all 115 positions of their relative adjustment.

5. In apparatus of the character stated, a chamber through which a web is passed having an entrance passage for the web, combined with feeding and guiding means for said passage comprising two fixed guides closely fitting the walls of the entrance passage and separated a short distance apart to provide a passage for the web over one guide in entering and over the other guide in leaving the chamber, a movable guide in alinement with the passage between the fixed guides and adapted to make a close fit with 125 130

- both guides, and means for moving the movable guide toward the fixed guides and between the web portions guided thereby with a yielding pressure.
- 5 6. In apparatus of the character stated, a chamber through which a web is passed having an entrance passage for the web, combined with feeding and guiding means for said passage comprising two fixed guides 10 closely fitting the walls of the entrance passage and separated a short distance apart to provide a passage for the web over one guide in entering and over the other guide in leaving the chamber, a movable guide in 15 alinement with the passage between the fixed guides and adapted to make a close fit with both guides, means for moving the movable guide toward the fixed guides and between the web portions guided thereby with a 20 yielding pressure, and means to adjust the extent of the yielding pressure.
7. In apparatus of the character stated, a chamber through which a web is passed having an entrance passage for the web, combined with feeding and guiding means for said passage comprising two fixed guides closely fitting the walls of the entrance passage and separated a short distance apart to provide a passage for the web over one 25 guide in entering and over the other guide in leaving the chamber, a movable guide in alinement with the passage between the fixed guides and adapted to make a close fit with both guides, means for moving the movable 30 guide toward the fixed guides and between the web portions guided thereby with a yielding pressure, and means to maintain the guides in a heated condition.
8. In apparatus of the character stated, a chamber through which a web is passed having an entrance passage for the web, combined with feeding and guiding means for said passage comprising two cylindrical tubular normally fixed guides arranged parallel at a short distance apart and respectively making a close fit with the top and bottom walls of the entrance passage, a movable cylindrical tubular guide of greater diameter than the space between the fixed 45 guides and adapted to rest upon the web part or parts passing between said fixed guides, and pivoted means for supporting the movable guide and pressing it toward the fixed guides with a yielding pressure.
- 50 9. In apparatus of the character stated, a chamber through which a web is passed having an entrance passage for the web, combined with feeding and guiding means for said passage comprising two cylindrical tubular normally fixed guides arranged parallel at a short distance apart and respectively making a close fit with the top and bottom walls of the entrance passage, a movable cylindrical tubular guide of greater 55 diameter than the space between the fixed guides and adapted to rest upon the web part or parts passing between said fixed guides, and pivoted means for supporting the movable guide and pressing it toward the fixed guides with a yielding pressure.
- 60 10. In apparatus of the character stated, a chamber through which a web is passed having an entrance passage for the web, combined with feeding and guiding means for said passage comprising two cylindrical tubular normally fixed guides arranged parallel at a short distance apart and respectively making a close fit with the top and bottom walls of the entrance passage, a movable cylindrical tubular guide of greater 65 diameter than the space between the fixed guides and adapted to rest upon the web part or parts passing between said fixed guides, and pivoted means for supporting the movable guide and pressing it toward the fixed guides with a yielding pressure, and means for supplying steam to the several guides and draining the water of condensation therefrom.
- 70 11. In apparatus of the character stated, a chamber through which a web is passed having an entrance passage for the web, combined with feeding and guiding means for said passage comprising two cylindrical tubular normally fixed guides arranged parallel at a short distance apart and respectively making a close fit with the top and bottom walls of the entrance passage, a movable cylindrical tubular guide of greater 75 diameter than the space between the fixed guides and adapted to rest upon the web part or parts passing between said fixed guides, said cylindrical guides being circumferentially adjustable to permit different portions of their surfaces to be brought into opposed relation to compensate for wear, pivoted means for supporting the movable guide and pressing it toward the fixed guides with a yielding pressure, and adjustable means for supplying steam to the several guides and draining the water of condensation therefrom said means including adjustable steam and drainage connections with the movable guide.
- 80 12. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for supplying a heating medium to said fixed portions and movable guide.
- 85 13. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 90
- 95 14. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 95
- 100 15. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 105
- 110 16. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 115
- 115 17. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 120
- 120 18. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 125
- 125 19. In apparatus of the character stated, a chamber through which a web is passed having an entrance passage for the web, combined with feeding and guiding means for said passage comprising two tubular fixed portions arranged at a distance apart to form a passage through which the web is guided, a movable tubular guide of larger diameter than the width of the passage between the fixed portions and adapted to make a close joint therewith and rest upon the web, yielding pressure applying means for yieldingly pressing the movable guide upon the web passing between the fixed portions, and means for adjusting the extent of the 130

yielding pressure, and means for supplying a heating medium to said fixed portions and movable guide.

13. In apparatus of the character stated, 5 a chamber through which a web is passed having an entrance passage for the web, combined with feeding and guiding means for said passage comprising two fixed portions between which the web is guided, a 10 tubular movable guide of larger diameter than the space between the fixed portions, means for yieldingly pressing the movable guide upon the web passing between the fixed portions, means for supplying steam 15 to the movable guide, and a flexible drainage hose connecting with the movable guide for conveying off the water of condensation.

14. In apparatus of the character stated, a chamber through which a web is passed

having an entrance passage for the web, 20 combined with feeding and guiding means for said passage comprising two fixed portions between which the web is guided, a tubular movable guide of larger diameter than the space between the fixed portions, 25 means for yieldingly pressing the movable guide upon the web passing between the fixed portions, said means including hinged arms carrying the movable guide at their free ends whereby it is maintained parallel 30 to the fixed portions, and means for supplying steam to the movable guide.

In testimony of which invention, I hereunto set my hand.

CHARLES H. ELLIOTT.
